UNITED STATES PATENT OFFICE.

WILLIAM E. WOODARD, OF SCHENECTADY, NEW YORK, ASSIGNOR TO AMERICAN LOCOMOTIVE COMPANY, OF NEW YORK, N. Y., A CORPORATION OF NEW YORK.

CAR-TRUCK.

No. 918,808.

Specification of Letters Patent. Patented April 20, 1909.

Application filed August 27, 1908. Serial No. 450,406.

To all whom it may concern:

Be it known that I, WILLIAM E. WOODARD, of Schenectady, in the county of Schenectady and State of New York, have invented a certain new and useful Improvement in Car-Trucks, of which improvement the following is a specification.

My invention relates to car trucks of the "Master Car Builders'" type, and its object is to provide a truck of such type which shall be of simplified construction and avoid the use of the bent equalizer forgings heretofore usually found necessary.

The improvement claimed is hereinafter fully set forth.

In the accompanying drawings: Figure 1 is a plan or top view, partly in section, of a car truck embodying my invention; Fig. 2, a side view, in elevation, of the same; Fig. 3, a half transverse central section; and, Fig. 4, a half transverse section in the plane of one of the axles.

In the practice of my invention, I provide a truck frame having two side members, each of which is an integral metal plate, and comprises a top bar, 1, a bottom bar or pedestal tie bar, 1^a, and pedestal jaws, 5, said side members being connected one to the other, on opposite sides of the transverse central plane of the truck, by two transoms, 2, which, in the instance shown, are of channel section, but may be of any other suitable and preferred form. The transoms are secured to the side members through the intermediation of filling castings, 3, the webs of which are bolted to the side members, and which have lateral flanges bolted to the transoms. The transoms and side members are also connected by gussets, 4, secured to them by vertical and horizontal bolts, the connections being preferably, as shown, made through the intermediation of angles, 1^b, which serve, further, to stiffen the side members.

Journal box guides or pedestal wear shoes, 5^b, are bolted to the outer sides of each pair of pedestal jaws, 5, between which guides are fitted the journal boxes, 9, which inclose the bearings, 9^a, for the journals, 8^a, of the axles, 8, on which the wheels, 7, of the truck, are secured. The journal box guides, 5^b, extend through the openings between the pedestal jaws, and project from the outer sides thereof practically throughout their entire width or transverse dimension, their projection from the inner sides of the side members be-

ing only for the slight extent which will suffice to enable the inner flanges of the journal boxes to clear them, and the frame side members, 1, are therefore located in vertical planes inside of, or nearer to the longitudinal central plane of the truck than, the vertical central planes of the journals, 8^a. The truck frame is movable vertically, relatively to the journal boxes, on which each of its side members is supported by a single equalizer, 10. The equalizers, 10, are straight bars, of rectangular section, which extend longitudinally adjacent to the outer sides of the side members, 1, from one of the journal boxes of each side member to the other, their vertical planes being in or near the vertical central planes of the journals, 8^a, and their ends resting on the tops of the journal boxes.

The side members are supported on the equalizers through the intermediation of helical equalizer springs, 11, which are coiled around spring rods, 12, suspended, at their upper ends, on, and depending from, the equalizers, said equalizer springs abutting, at their lower ends, on spring seats, 12^a, fitted on the spring rods, and, at their upper ends, on spring seats, 12^b, bolted to the adjacent side member, below the equalizer, through upwardly and downwardly extending lateral flanges.

A spring plank, 13, is suspended from the transoms, 2, by swing hangers, 14, journaled on swing hanger pivot bearings, 15, which are fitted in swing hanger pivot bearings, 16, on the tops of the transoms. A swing bolster, 17, which, in this instance, is shown as of U or channel section, and having its vertical members stiffened by angles, 17^a, but which may be of any other preferred form, is supported on the spring plank by semi-elliptic bolster springs, 19, two pairs of which are interposed between the spring plank and seats, 17^b, located near each of the ends of the bolster. The webs of the filling castings, 3, of the transoms, serve as end stops for the bolster and wear plates for the adjacent ends thereof. A center casting, 20, and side bearings, 21, of the ordinary form, are secured to the bolster, at the middle and ends, respectively.

The form and relation of the side members and pedestals above described are such as to simplify the construction and minimize the number of parts of the truck frame, and attain the further substantial advantage of

enabling single straight equalizers to be applied, instead of pairs of equalizers having upwardly bent ends, as heretofore employed, and, by reason of the frame construction used, necessary in, trucks of the M. C. B. type. The forgings for equalizers of the latter form are more complicated and difficult to make, and are subject to the risk of injury in bending, from which the straight 10 equalizers are entirely exempt.

I claim as my invention and desire to secure b. Letters Patent:

In a car truck, the combination of two 15 plate metal side frame members, having pairs of integral pedestal jaws adjacent to their ends, journal box guides fixed to and projecting, for the major portion of their transverse dimension, from the outer sides of the pedestal jaws, axles journaled in jour-

nal boxes fitting between said journal box 20 guides, wheels fixed on said axles, transoms interposed between the side frame members on opposite sides of the transverse central plane of the truck, filling castings bolted to the side frame members and to the transoms 25 between the ends of the latter, angle plates secured to the side frame members and extending from the transoms to the pedestal jaws, gussets secured to said angle plates and to the transoms, single straight bar equalizers supported on the axles exterior to the side frame members, and equalizer springs interposed between and bearing on said equalizers and the side frame members.

WILLIAM E. WOODARD.
